UNITED STATES PATENT OFFICE.

WILLIAM WALLACE WEEKS, OF BROOKLYN, NEW YORK, ASSIGNOR TO ELEVATOR SUPPLIES COMPANY, INC., A CORPORATION OF NEW JERSEY.

ELEVATOR-DOOR CLOSER AND SWITCH.

Application filed October 27, 1923. Serial No. 671,124.

To all whom it may concern:

Be it known that I, WILLIAM WALLACE WEEKS, a citizen of the United States, residing at 366 Fourth Street, Brooklyn, New York, have invented a certain new and useful Improvement in Elevator-Door Closers and Switches, of which the following is a clear, full, and exact description.

The present invention relates to an elevator door closer and switch combined therewith, and more particularly to a pneumatically-operated closer having cushioning means and a switch combined therewith in one apparatus to operate as a unit and in which the switch is operated with the opening and closing movements of the door.

The primary object of the present invention is to provide a combined pneumatic elevator door closer and switch in which the switch is operated in oil and which is adapted to be opened and closed with the movements of the closer.

Another object of the invention is to provide a switch in a pneumatically-operated elevator door closer which is adapted to be connected in the controller circuit of an elevator and which is so disposed in the device as to substantially prevent tampering with the switch connections to short circuit the switch or to disconnect it.

Another object of the invention is to provide an improved form of operating means to open a switch in a closer of the form above referred to.

With these and other objects in view, the invention comprises various features hereinafter described and defined in the claims.

The preferred embodiment of the invention is illustrated in the accompanying drawings, in which—

Fig. 1 is a sectional view in elevation of a device embodying the preferred form of my invention;

Fig. 2 is a section taken on the line 2—2 of Fig. 1;

Fig. 3 is a section taken on the line 3—3 of Fig. 1;

Fig. 4 is a cross section taken on the line 4—4 of Fig. 1; and

Fig. 5 is a sectional view on a reduced scale taken on the line 5—5 of Fig. 1.

In the operation of elevator doors by pneumatic closers, the closer is in general mounted in proximity to the elevator door and is attached by suitable connections to

the toggle levers thereof, by means of which the elevator door is operated. In connection with closers heretofore employed for operating elevator doors, a switch, in the controller circuit of the elevator, was connected by some means, as levers, to the toggle levers of the elevator door by means of which the switch was opened and closed with the opening and closing movements of the door.

The use of a separate switch for opening and closing the controller circuit is objectionable for the reason that the switch may be readily disconnected so that it will fail to open the circuit when the elevator door is opened. By disconnecting the switch the elevator may be operated more rapidly but the danger to passengers is increased due to the possibility of operating the elevator while the doors are open, which it is the purpose of the switch to overcome.

In the present form of my invention, a switch is embodied in the pneumatically-operated closer in such a manner that it is not accessible to be tampered with and is of a form which may be readily adjusted so as to open and close the elevator controller circuit at predetermined positions in the opening and closing movements of the elevator door, as will be hereinafter fully described.

In Fig. 1 of the drawings, 2 designates a casing of the operating cylinder to which is attached an upper head or cap 4 which is attached thereto by suitable connections such as a screw-threaded connection 6, for instance. Within the casing 2 is a piston 8 having a leather washer 10 attached thereto which may be expanded so as to attain a close sliding connection with the walls of the cylinder by means of a follower or expanding element 12. To the lower portion of the cylinder casing 2 is attached a cushioning means comprising a plunger 14 operating within a plunger cylinder 16. The plunger 14 has attached thereto a plunger rod 18 which passes upwardly through the plunger cylinder and through openings in the follower, the leather washer and the piston, and through a sleeve 20 which is rigidly attached to the piston 8, through the head 4, and is attached by suitable connections to the toggle levers of the elevator door. In order that the plunger and the plunger rod may be operated to open and

close the elevator door through the toggle levers, the sleeve 20 is rigidly connected by a jam nut or other suitable connecting means which may be readily disconnected so that 5 the piston sleeve may be detached from the plunger rod. By this means the plunger and parts attached thereto may be readily withdrawn from the apparatus to replace worn parts or to make adjustments, if desired.

Between the piston 8 and the upper head 4 is a spring member 22 which in the upward movement of the piston 8 is compressed and which will serve to return the 15 piston after operation thereof to cause opening of the elevator door. Air or other pressure fluid is admitted into the cylinder casing 2 below the piston 8 through one or more inlet pipes 24, 26, the admission of 20 pressure fluid therein being controlled by a suitable valve or valves.

The lower end of the cylinder 16 is preferably closed by means of a head 28 which may be connected thereto through screw-threaded connections 30, and which has attached thereto a lug 32 which may be readily attached to a bracket or other means for placing the closer in operative position. The cylinder 16 is preferably attached to the 25 cylinder casing 2 by means of a casing 34 which is preferably connected to the cylinder at a mid-portion thereof and made integral therewith so as to form a reservoir 36 between the walls of the casing 34 and 30 the cylinder 16. The casing may be attached to the cylinder casing 2 by suitable means such as screw-threaded connections 38. Within the walls of the cylinder 16 are 35 oil passageways 40, 42 connecting the lower 40 and upper portions of the cylinder with an enlarged mid-portion 44 thereof. Within the oil passages are suitable regulating screws 46, 48 by means of which the passage 45 of oil through the passageways may be controlled, so as to control the movements of the plunger 14 within the cylinder 16, by means of which any desired amount of cushioning in the movements of the elevator door may be attained. The passage of oil 50 from the cylinder 16 and the reservoir 36 into the cylinder casing 2 is prevented by means of a bushing 50 around the plunger rod 18 and by means of a perforated diaphragm 52 which is held in place within a 55 recess in the casing 34. The diaphragm 52 has a number of perforations or openings 54 therein through which a small amount of oil spray passes and serves to lubricate the cylinder walls 2 and to keep the leather 60 washer soft and pliable.

In order to provide a switch in the device which may be connected to the controller circuit of the elevator and which may be operated in oil, I place two terminals 56, 58, 65 which may be attached in the walls of the

casing 34, at the lower end thereof. In order to suitably insulate the terminals 56, 58 from the metal casing 34, I provide insulating members 60 around the terminals through which the terminals project into a recess or casing 62, in which the controller circuit leads are connected to the terminals by suitable connecting means such as nuts 66. The leads 64 may be suitably protected by a conduit 68 leading into the casing 62, 70 and a cover member 70 is attached to the casing 62 by set screws, a lock, or other suitable means, whereby tampering with the leads or switch connections may be entirely prevented. A conducting member 72 in the 75 form of an annular segment is provided which may be lowered and raised into and out of contact with the switch terminals whereby closing and opening of a circuit therethrough is attained. The conducting 80 member 72 is attached to an insulating block 74 of similar form to the segment 72, so that it may be raised and lowered within the reservoir 36, and is of such a size as to prevent swinging movement therein. The insulating member 74 has an upstanding portion 76 having a shoulder or projecting portion 78 by means of which an attaching member 80 may be employed to contact therewith to raise and lower the insulating member 74 85 and conducting member 72 connected therewith. The means which I preferably employ is a rod passing downwardly through a suitable opening in the diaphragm 52 and which has a head or support 80 which is adapted to cooperate with the shoulder 78 by means of which the parts may be raised out of contacting position with the terminals. Between the head 80 and the insulator 74 is a spring member 82 which is adapted to be set in a recess 84 in the insulator 74 and which may be held in place by means of a projection 86 from the head 80. By means of the spring 82 the conductor 72 90 may be held in pressure contact with the terminals 56 and 58, and a limited movement of the piston may thus take place, corresponding to a limited movement of the elevator door, before the circuit through the 95 switch terminals is broken.

A release mechanism is employed in order to release the conducting member after it has been brought up out of contact with the switch terminals. The form of release mechanism which I preferably employ comprises an annular ring member having a circular or annular recess 88 therein, as shown in Fig. 1 of the drawings. The annular ring member is preferably made integral with the follower 12. A square connecting rod 90, which is twisted in a portion of its length, passes through a corresponding square opening 92 in the diaphragm 52 by means of which the rod 125 is turned in position when moved upwardly 130

and downwardly by means of the piston. The rod 90 is connected at one end by a 5 slideable spring pressed connection, as has been described, to the insulating member 74, by means of which the conducting member 72 is held in pressure contact with the terminals 56, 58 when the piston is in its lower-most position. At the upper end of the rod 90 is a shoulder 91 by means of 10 which a spring member 94 is normally held in compression against the upper portion of the diaphragm 52. The spring 94 serves to hold the rods and parts attached thereto in raised position after the rod has been 15 pulled upwardly by means of the piston to break the circuit through the switch terminals.

Attached to the upper portion of the rod 90 is a cylindrical rod 98 which may be 20 made integral with the rod 90 if desired. In the upper portion of the rod 98 or attached thereto, is a pin or laterally projecting member 96 adapted to cooperate with the groove or recess 88 to draw the connecting rod 90 and parts attached thereto upwardly with the movements of the piston. When the piston is in its lowermost position corresponding to the closed position 25 of the elevator door, the pin 96 extends 30 in a radial direction in the annular recess 88 so that it bridges the recess and rests upon the projecting shoulders therein. As the piston moves upwardly, the rod 90 is twisted by means of the corresponding 35 opening in the diaphragm 52 and the pin 96 is thereby twisted through an angle of substantially 90°, whereby it is released and the piston passes upwardly leaving the rod and conducting member 72 in raised position. 40 In the upward movement of the piston the rod 90 moves upwardly a predetermined distance, depending upon the distance which the shoulder 80 moves before coming into contact with the shoulder or 45 projection 78. During this time the spring 82 maintains a pressure contact between the conducting member 72 and the terminals 56, 58. After the head 80 attached to the rod 90 comes into contact with the shoulder 50 78, the conducting member and parts attached thereto are drawn upwardly until the rod 90 is disconnected from the piston by the turning movement, in which the pin 96 turns in the recess 88 so as to be released. 55

During the closing movement of the elevator doors which takes place after fluid pressure has been cut off by means of a 60 valve, the spring 22 returns the piston 8, and the follower 12 containing the recess 88 comes in contact with the rod 96 attached to the rod 90 and forces the rod and conducting member with its attached parts downwardly into closing position of the 65 switches. In the downward movement of

the rod 90, the rod is twisted through an angle corresponding to the angle of twist therein by means of the guide opening in the diaphragm, and the pin 96 is turned so as to lock the rod in position until the piston is again drawn upwardly to release the rod, as heretofore explained. In the downward movement of the piston the conducting member 72 comes into contact with the switch terminals 56, 58 at a predetermined point before the door is entirely closed. This point may be regulated by suitably proportioning the length of the rod 90. Under ordinary conditions I prefer to have the switch in the elevator controller circuit closed when the elevator door approaches within a half inch of its closed position. It is to be understood, however, that the point at which the closer of the switch takes place may be varied to suit the requirements under operating conditions.

It is to be understood that various changes and modifications may be made in the details of the device, as will appear to those skilled in the art, without departing from the spirit or scope of the invention as defined in the claims.

Having thus described the invention, what is claimed as new is:

1. In an elevator door closer, a casing, a piston therein, means for admitting pressure fluid to operate said piston, switch terminals in said casing, a conducting member, means for maintaining oil around said terminals and conducting member, and means for moving said conducting member into and out of contact with said terminals, whereby a circuit therethrough may be opened and closed. 100

2. In a power-operated closer, a casing, a piston therein, means for admitting pressure fluid to said casing to operate said piston, switch terminals in said casing, a conducting member, means for maintaining oil around said terminals and conducting member, and means for moving said member into and out of contact with said terminals, whereby a circuit therethrough may be opened and closed. 110

3. A combined elevator door closer and switch comprising a casing, a piston in said casing, means for admitting pressure fluid to said casing to operate said piston, a switch in said casing adapted to be connected to the controller circuit of an elevator comprising terminals and a conducting member, means for maintaining oil in contact with said terminals and conducting member, and means for moving said conducting member into and out of contact with said terminals during opening and closing movements of the elevator door to open and close the controller circuit. 120

4. In an elevator door closer, a casing, a 130

piston in said casing, means for admitting pressure fluid to said casing to operate said piston, a switch in said casing adapted to open and close the elevator controller circuit, said switch comprising switch terminals passing through said casing, means for insulating the terminals from the casing, a conducting member within said casing adapted to be moved into and out of contact with said terminals during opening and closing movements of said elevator door, means for connecting the leads of said circuit to said terminals exterior to said casing, a casing around the connections, and means for locking said casing to prevent unauthorized access thereto.

5. A combined elevator door closer and switch comprising a casing, a piston in said casing, means for admitting pressure fluid to said casing to operate said piston, switch terminals in said casing, a conducting member, means for maintaining a bath of oil around said terminals and conducting member, means for operatively connecting said conducting member to said piston, whereby said conducting member will be moved into and out of contact with said terminals with the movements of said piston, and means for holding said conducting member in pressure contact with said terminals during contact therewith.

6. A combined elevator door closer and switch comprising a casing, a piston in said casing, means for admitting pressure fluid below said piston to cause operation thereof, spring means in said casing for returning said piston, switch terminals in said casing, a conducting member, means for maintaining oil around said terminals and conducting member, means for operatively connecting said conducting member to said piston to move said conducting member out of contact with said terminals when said piston is operated, and means for disconnecting said conducting member from said piston when said conducting member has been moved a predetermined distance out of contact with said terminals.

7. A combined elevator door closer and switch comprising a casing, a piston in said casing, means for admitting pressure fluid to operate said piston, switch terminals in said casing, a conducting member, means for maintaining oil around said terminals and conducting member, means for operatively connecting said conducting member to said piston to move said conducting member out of contact with said terminals, and means for disconnecting said conducting member from said piston when the said conducting member has been moved a predetermined distance out of contact with said terminals.

8. A combined elevator door closer and switch comprising a casing, a piston in said

casing, means for admitting pressure fluid to said casing to operate said piston, switch terminals in said casing, a conducting member, means for maintaining oil around said terminals and conducting member, means for operatively connecting said conducting member to said piston whereby said conducting member will be moved into and out of contact with said terminals with the movements of said piston, means for holding said conducting member in pressure contact with said terminals during contact therewith, and means for disconnecting said conducting member from said piston when said conducting member has been moved a predetermined distance out of contact with said terminals.

9. A combined elevator door closer and switch comprising a casing, a piston in said casing, means for admitting pressure fluid below said piston to cause operation thereof, spring means in said casing for returning said piston when the fluid pressure is released, switch terminals in said casing, a conducting member, means for maintaining a body of oil in contact with said terminals and conducting member, means for operatively connecting said conducting member to said piston to move said conducting member out of contact with said terminals, means for disconnecting said conducting member from said piston when said conducting member has moved a predetermined distance out of contact with said terminals, means for locking said connecting means when said piston returns to its initial position, and means for holding said conducting member in pressure contact with said terminals when said switch is closed.

10. A combined closer and switch comprising a casing, a piston in said casing, means for admitting pressure fluid into said casing to operate said piston, switch terminals in said casing, a movable conducting member in said casing, means for maintaining a body of oil in contact with said terminals and conducting member, means for operatively connecting said conducting member to said piston to move said conducting member into and out of contact with said terminals with movements of said piston, and means whereby said piston may be moved a predetermined amount within said casing before said conducting member is brought out of contact with said terminals and whereby the circuit through said terminals is completed at a predetermined point in the return movement of said piston.

11. A combined elevator door closer and switch comprising a casing, a piston in said casing, means for admitting pressure fluid to operate said piston, cushioning means in said casing for cushioning the movements of said piston, switch terminals in said casing, a conducting member, means for main-

5 taining a body of oil in contact with said terminals and conducting member, means for operatively connecting said conducting member to said piston to move said conducting member into and out of contact with said terminals with the movements of said piston, and means for disconnecting said conducting member from said piston when said conducting member has been 10 moved a predetermined distance out of contact with said terminals.

12. A combined elevator door closer and switch comprising a casing, a piston in said casing, means for admitting pressure fluid into said casing to operate said piston, switch terminals in said casing, a conducting member, means for maintaining a body of oil in contact with said terminals and said conducting member, means for operatively connecting said conducting member to said piston to move said conducting member into and out of contact with said termi-

nals with movements of said piston, the last-named means comprising spring means for holding said conducting member in 25 pressure contact with said terminals during contact therewith, a connecting rod operatively attached to said conducting member, said connecting rod being twisted at an angle in a portion of its length, a stationary 30 guide for said rod whereby said rod is turned in the upward and downward movement thereof, locking means for said rod adapted to lock said rod to said piston when said piston is lowered, said locking means 35 operating to release said connecting rod and parts attached thereto when said piston is moved upwardly a predetermined distance, and means for holding said conducting member in raised position after said piston 40 has moved upwardly.

Signed at New York, New York, this 25th day of October, 1923.

WILLIAM WALLACE WEEKS.
